Primary Examiner — Katie Jane Stofko

(57) **CLAIM**

The ornamental design for a recreational pit, as shown and described.

DESCRIPTION

FIG. 1 is a front and top perspective view of a recreational pit showing our new design;

FIG. 2 is a front elevation view thereof;

FIG. 3 is a left-side elevation view thereof, a right-side elevation view thereof being a mirror image of the left-side elevation view;

FIG. 4 is a rear elevation view thereof;

FIG. 5 is a bottom view thereof; and,

FIG. 6 is a top view thereof.
